(57) **CLAIM**

The ornamental design for a vehicle interior, as shown and described.

DESCRIPTION

FIG. 1 is a front, top, left side perspective view of a vehicle interior showing our design.

FIG. 2 is a rear, top, left side perspective view thereof.

FIG. 3 is a rear, top, right side perspective view thereof.

FIG. 4 is a front, top, right side perspective view thereof, shown in a second configuration; and,

FIG. 5 is a rear, top, right side perspective view thereof.

The broken lines depict a boundary around the de-emphasized elements, which illustrate portions of the vehicle interior which form no part of the claimed design.

1 Claim, 5 Drawing Sheets

FIG. 1

FIG. 2

FIG. 3

FIG. 4

FIG. 5
